United States Patent Office

Des. 190,652
Patented June 20, 1961

190,652

DESK

John A. Borden, 321 Camino Real W., Apt. 201,
Boca Raton, Fla.

Filed July 28, 1960, Ser. No. 61,553

Term of patent 14 years

(Cl. D33—7)

The dominant portions of my design are shown in full lines on the drawing.

I claim:

The ornamental design for a desk, as shown and described.
